UNITED STATES PATENT OFFICE.

JOSEPH N. BURON, OF SANTA BARBARA, CALIFORNIA.

SAFETY STIRRUP.

Application filed April 13, 1925. Serial No. 22,784.

To all whom it may concern:

Be it known that I, JOSEPH N. BURON, a citizen of Canada, residing at Santa Barbara, in the county of Santa Barbara, State of California, have invented certain new and useful Improvements in Safety Stirrups; and I do hereby declare the following to be a full, clear, and exact description of the invention, such as will enable others skilled in the art to which it appertains to make and use the same.

This invention relates to new and useful improvements in stirrups, and particularly to safety stirrups.

One object of the invention is to provide a stirrup which is simple in construction, and which will be comfortable to the foot of the rider.

Another object is to provide a stirrup which will protect the foot from moisture, while riding through wet grass or underbrush, while at the same time providing for proper ventilation to the foot.

Another object is to provide a stirrup of this character which will easily and quickly slip from the foot, should the rider be thrown from the horse.

Other objects and advantages will be apparent from the following description when taken in connection with the accompanying drawing.

In the drawing:

Figure 1 is a side elevation of a stirrup made in accordance with the present invention.

Figure 2 is a top plan view of the same.

Figure 3 is a vertical longitudinal central sectional view through the stirrup.

Figure 4 is a vertical transverse sectional view on the line 4-4 of Figure 2.

Referring particularly to the accompanying drawing, 10 represents an angular U-shaped strap of metal, having on the upper ends of the arms thereof the loops 11, for the reception of the ends of the suspending strap 12. Secured at its rear end to the transverse portion of the U-shaped strap 10 is the forwardly extending metal foot plate 13, said plate being longitudinally curved to conform to the curvature of the sole of the shoe of the rider. Secured to the longer edge portions of the plate 13 is the upwardly arched metal plate 14, such plate combining with the plate 13 to form an enlarged shoe or boot, the forward ends of said plates being cut off, to provide an open-

ing 15, through which the tip of the toe of the rider's shoe protrudes. The upper portion of the arched plate 14 is formed with a longitudinal flat section 15', and formed in this section is the longitudinal slot 16, the forward or lower end of said slot having its wall partly separated to provide tab or lug 17. Disposed on this flat section 15', and extending longitudinally thereof, in covering relation to the slot 16, is a metal plate 18, and formed on this plate is the housing 19, within which are mounted the two rollers 20. These rollers protrude inwardly through the slot to a sufficient distance to be engaged by the toe of the rider's shoe or boot, so that should the rider be thrown from the horse, the foot will easily slide from the stirrup, thereby preventing an accident to the rider. Carried by this flat section 15', at the other end of the slot 16, is a turn-button 21, which is arranged to be received in a notch or kerf 22, in the adjacent end of the plate 18, whereby to hold the plate at this end. The other end of the plate 18 is formed with a struck out tab 23, which is slipped beneath the tab 17, so that an interlocking engagement is established between the plates 14 and 18, to hold the lower end of the plate 18 removably in place.

Extending rearwardly from the transverse member of the strap 10 are the spaced lugs 24, between which the heel of the rider's shoe is held to prevent sidewise movement thereof.

The arched plate 14 effectively protects the foot from becoming wet when contacting with underbrush, while at the same time the opening in the forward end of the stirrup permits free access of air to ventilate the rider's foot.

What is claimed is:

1. A stirrup including a foot receiving member having an opening in its upper portion, a rotatable member mounted on the said member and having a portion thereof projecting into the member through said opening, said rotatable member being arranged for contact with the rider's foot to facilitate the withdrawal thereof from the stirrup, and a covering means for the outer portion of said rotatable member.

2. A stirrup including a foot receiving member having an opening in its upper portion, suspending means for the foot receiving member, a casing mounted in covering relation to said opening, and a rotatable

member mounted in the casing and extending into the foot receiving member for contact with the rider's foot to facilitate the withdrawal thereof from the stirrup.

5 3. A stirrup including a foot receiving member having an opening in the forward end thereof and a slot in the upper portion thereof, suspending means for the stirrup, a casing removably secured on the foot re-

ceiving member in covering relation to said slot, and rollers in the casing and protruding through the slot for contact with the foot of the rider to facilitate the withdrawal of the foot.

In testimony whereof, I affix my signature.

JOSEPH N. BURON.
